UNITED STATES PATENT OFFICE.

HERMANN CLAUSSEN, OF BROOKLYN, NEW YORK.

HANGER.

1,018,097.

Specification of Letters Patent. Patented Feb. 20, 1912.

Application filed September 25, 1909. Serial No. 519,576.

To all whom it may concern:

Be it known that I, HERMANN CLAUSSEN, citizen of the United States, residing at Brooklyn, in the county of Kings and State 5 of New York, have invented certain new and useful Improvements in Hangers, of which the following is a specification.

This invention relates to certain new and useful improvements in hangers for hats, 10 coats and the like, designed to be made portable so as to be carried in the pocket, bag, or gripsack and applied in any desired position.

It comprises broadly a supporting member 15 having pins or projections adapted to be pressed into a partition or other suitable support and a member having pivotal connection therewith and designed, when closed, to fold against or parallel with the supporting member and to protect the pins or projections thereon. When in its operative position this protective member serves as a support for one or more garments.

The device as a whole is simple in its 20 nature being composed of two members and it serves when in use to perform its function in a most serviceable and efficient manner.

Other objects and advantages of the invention will hereinafter appear and the 25 novel features thereof will be particularly pointed out in the appended claim.

The invention is clearly illustrated in the accompanying drawings, which, with the numerals of reference marked thereon, form 30 a part of this specification, and in which,

Figure 1 is an elevation of my improved device with the members in their closed position. Fig. 2 is a side elevation showing the members in position for use. Fig. 3 is an elevation of the supporting member of Fig. 2 35 detached. Fig. 4 is a perspective detail on an enlarged scale showing the construction of the protecting member at the junction of its two arms.

Like numerals of reference indicate like 40 parts throughout the several views.

Referring to the drawings, 1 designates 45 a supporting member, having at one end a hook shaped member 2, the rear face being preferably flat as seen at 3 and provided with pins or projections 4 as seen clearly in Figs. 1, 2 and 3 which operates the pins or projections normally at an angle in-

clined slightly downward at an angle somewhat less than a right angle to the rear 55 face, to support member 1 as seen clearly in Fig. 3.

5 is a member having its ends, 6 and 7 extend at substantially a right angle to its body portion, as seen in 7 being bent upon 60 itself to form a substantially semi-circular portion 8, having an extension 9 which is at substantially a right angle to the end member 7. The extension of the guard member 65 normally engages the hook member 1 so that when the end 6 is released from the hook member the guard will be thrown away from the hook member by reason of the spring extension of said guard member. Within this curved portion 8 is received a 70 slotted portion 10 of the member 1, as seen clearly in Figs. 1 and 2. The member 10 is received within the eye of the grooved portion 8 and the entrance to said eye is then substantially or partially closed as shown 75 in Figs. 1 and 2 so as to prevent ready displacement of the parts, yet allow of free movement of the one with relation to the other. In practice the device is applied as seen in Fig. 2. The pins 4 are pressed into 80 the wall or other fixed support 12 until the flat face engages said support. Then when weight is applied to the member 1 the inclination of the pins 4 serves to prevent the member 1 from being pulled out, said pins 85 in 1 assuming a substantially horizontal position as seen in Fig. 2.

When not in use the device is closed as seen in Fig. 1, when the member 5 serves as a guard to protect the pins 4. When not in 90 use the member is frictionally secured in a hole 13 of the hooked member 1 as seen in Fig. 1. When in use this guard member 5 is thrown over into the position in which it is seen in Fig. 2, where it serves as a support 95 for coats or other articles of wearing apparel.

Sometimes the guard 5 may be omitted and the member 1 used alone as indicated in Fig. 3.

Modifications in detail may be resorted to without departing from the spirit of the invention or sacrificing any of its advantages.

What is claimed as new is:—

In a coat hanger, a hook member having

100

105

fasteners projecting therefrom and formed at one end with an eye, a guard member having one end pivoted to the eye and formed with a resilient extension adapted to bear against the hook member when the guard is closed thereon, said extension projecting outwardly of the hook member when the guard is open, and an end extension car-

ried by the guard member adapted to be snapped to the hook member. 10

In testimony whereof I affix my signature, in presence of two witnesses.

HERMANN CLAUSSEN.
